UNITED STATES PATENT OFFICE.

CLARENCE ARTHUR GRAHAM, OF COLUMBUS, OHIO.

DEVICE FOR TRUING MUSICAL STRINGS.

SPECIFICATION forming part of Letters Patent No. 729,326, dated May 26, 1903.

Application filed October 22, 1902. Serial No. 128,270. (No model.)

To all whom it may concern:

Be it known that I, CLARENCE ARTHUR GRAHAM, a citizen of the United States, and a resident of Columbus, in the county of Franklin and State of Ohio, have invented a new and Improved Device for Truing Musical Strings, of which the following is a full, clear, and exact description.

Strings for musical instruments formed of catgut and the like are generally of non-uniform diameter, and this defect impairs the musical accuracy of their notes.

The object of this invention is to overcome the defect mentioned, and this end is attained by providing a peculiarly-constructed grinding device to the action of which the string is subjected, so that the surface of the string is cut or ground down into true uniformity.

This specification is an exact description of one example of my invention, while the claims define the actual scope thereof.

Reference is to be had to the accompanying drawings, forming a part of this specification, in which similar characters of reference indicate corresponding parts in all the views.

Figure 1 is a perspective view of the invention, and Figs. 2 and 3 are cross-sectional views illustrating the invention as used with strings of different diameters.

The device comprises two oppositely-arranged end or finger pieces *a*, between which extends a body-plate *b*, rigidly fastened to the end plates and provided on its inner side with an abrasive covering *b'*.

c indicates a plate mounted to swing toward and from the plate *b* around the axis indicated at the points *c'* in the drawings. This plate is provided on its inner surface with an abrasive covering *c'*, similar to and opposing the covering *b'*.

The end or finger plates *a* are formed with a number of graduated openings *a'* therein, said openings being arranged in pairs the members of which are one in each end plate and are longitudinally alined, so that the string (indicated at *x* in the drawings) may pass through the end plates and between the two sections *b* and *c*.

d indicates a thumb-screw mounted in the body-plate *b* and adapted to limit the movement of the plate *c* toward the body-plate,

and *e* indicates a thumb-nut which works on a screw-stud *e'*, pivoted to lugs *b'* on the body-plate *b* and adapted to lie loosely between the oppositely-located lugs *c'* on the swinging plate *c*. By means of these parts the plate *c* may be pressed firmly toward the plate *b*, and by the adjustment of the screw *d* the plates *b* *c* may be made to engage the string with the required degree of force.

In using the invention the string is passed through that pair of openings *a'* which is suited to the general diameter of the string, and then the elements *d* and *e* are adjusted to cause the abrasive surfaces *b'* and *c'* to bear properly against the string. After this has been done the device should be grasped in the fingers (this can be most conveniently effected by engaging the thumb and forefinger with the end plates *a*) and the device moved along the string and simultaneously turned around the longitudinal axis thereof. The string should meanwhile be held stationary, and by this operation every part of the surface of the string may be reached by the abrading-surfaces, and the string will be cut down into strictly-uniform diameter. It will be observed that during this operation the screw *d* prevents the swinging plate *c* from moving up any farther than the operator intends, which movement would otherwise take place as the string is cut down by the action of the abrasive surfaces on the body and swinging plates.

Various changes in the form, proportions, and minor details of my invention may be resorted to without departing from the spirit and scope thereof. Hence I consider myself entitled to all such variations as may lie within the intent of my claims.

Having thus described my invention, I claim as new and desire to secure by Letters Patent—

1. A device for truing musical strings, comprising end members, and side plates having abrasive surfaces connecting said end members, substantially as set forth.

2. A device for truing musical strings, comprising two end members, and two side members connecting the end members, one of said side members being movable relatively to the other, substantially as set forth.

3. A device for truing musical strings, com-

prising two end portions provided with series of graduated apertures in alinement, a longitudinally-extending member holding the said end portions rigidly spaced apart, said 5 longitudinal member having an abrasive surface, and a second longitudinal abrading member pivoted to the aforesaid end portions, and movable on its pivot toward and from the rigid abrading member, substantially as set forth.

4. A device for truing musical strings, comprising two members having opposing abrading-surfaces, one of said members being rigidly mounted, the other member being pivotally mounted and movable from its pivot toward and from the rigid member, means for holding the strings in a certain and predetermined position relative to said abrading members, and means carried by the rigid 15 member for limiting the movement of the pivoted member toward said rigid member, substantially as set forth.

5. A device for truing musical strings, comprising two members having opposing abrasive surfaces, one of said members being rigid and the opposite member being movable, and means supported by one of the members for limiting the outward movement of the movable member away from the rigid member, substantially as set forth.

6. A device for truing musical strings, comprising a rigid abrading member, and a movable abrading member, means carried by the rigid member for limiting the movement of the

movable member toward said rigid member, 35 and adjustable means supported by one of said members for limiting the movement of the movable member away from the rigid member, substantially as set forth.

7. A device for truing musical strings, comprising opposite end plates adapted to have a string passed through them, two members mounted on the end plates and having abrasive surfaces adapted to have a string passed between them, one of said members being 45 swingable relative to the opposite member, and adjustable means carried by one of said plates for limiting the movement of the swing member toward and away from the opposite plate, substantially as set forth.

8. A device for truing musical strings, comprising orificed end plates, a body-plate held between them, a second plate movable toward and from the body-plate, said plates having opposing abrading-surfaces, adjustable means carried by one of said plates for limiting the movement of the movable plate toward the body-plate, and means for releasably holding the movable plate engaged with said adjustable means.

In testimony whereof I have signed my name to this specification in the presence of two subscribing witnesses.

CLARENCE ARTHUR GRAHAM.
